UNITED STATES PATENT OFFICE.

JOSEPH COOPER, JOHN FRANCIS WHITE, AND LOUIS COOPER, OF BRADFORD, ENGLAND;
SAID WHITE ASSIGNOR TO SAID JOSEPH COOPER AND SAID LOUIS COOPER.

COMBING-MACHINE FOR WOOL AND OTHER SIMILAR FIBERS.

No. 911,115.

Specification of Letters Patent.

Patented Feb. 2, 1909.

Application filed April 17, 1906. Serial No. 312,240.

To all whom it may concern:

Be it known that we, JOSEPH COOPER, JOHN FRANCIS WHITE, and LOUIS COOPER, British subjects, and residents all of Bradford, county of York, England, have invented certain new and useful Improvements in Combing-Machines for Wool and other Similar Fibers, of which the following is a specification.

10 This invention relates to improvements in Noble's combing machines for combing wool and other similar fibers. These combs have hitherto been constructed with a driving shaft mounted above the carriage upon two pillars from which vertical shafts are driven by bevel gearing inclosed in boxes at the tops of the pillars. The construction of these pillars with gearing boxes at their upper ends and horizontal driving shaft carried between them is an objectionable feature and renders the removal of the smaller or inner comb circle difficult as the gearing has first to be removed and it further restricts the machine to the use of two inner circles whereas by our 25 improvements we find that three or more inner or smaller comb circles can be employed thereby greatly increasing the output or productive capacity of the machine.

The invention will be fully described with 30 reference to the accompanying drawings in which sufficient of a Noble's combing machine is shown to illustrate the invention.

Figure 1. is a half sectional elevation of the machine on line $x-x$ Fig. 3. showing one combing head. Fig. 2. is a half sectional elevation of the machine on line $y-y$ Fig. 3. showing the carriage drive gearing. Fig. 3. is a partial plan of the apparatus. Fig. 4. is a plan of the gear plate M from below showing 40 the driving chains and gear wheels.

The outer carriage A the outer comb circle B, the upright or frame C for supporting the same, the outer drawing off rollers D the sliver box E and the inner drawing off rollers F are all constructed in the ordinary way, and no further description of them will be necessary. Inside the outer carriage A and outer comb circle we mount three inner carriages G and inner comb circles g each working 45 separately in conjunction with the outer comb circle B. The inner carriages G are mounted upon a three armed bracket G' one on each arm, the bracket G' being bolted to or mounted upon the uprights or frame C. 50 Upon each arm of the bracket G' we also

mount a hollow pillar H. Each pillar H is constructed without any gear box or gearing at the top and is therefore much shorter than formerly with the central driving shaft K which passes through it driven from below 60 by a sprocket or gear wheel k. By this construction we are enabled to employ three or more inner circle carriages G and inner combs g and also to remove and replace any one of the inner circle carriages or combs without 65 displacing or removing any of the driving gear.

The ball race a upon which the outer carriage A rotates is supported upon a number of brackets A' each adjusted by a small screw 70 a' and bolted to the frame or upright C by a bolt a².

The ordinary driving gear on the top of the pillars being dispensed with the several parts of the machine are driven by chain or other 75 gearing beneath the gear plate M by which a regular and steady drive is imparted to the machine. The driving is effected by a driving belt onto a pulley 1 on either of the studs 3, 4 or 5 and the motion is transmitted therefrom to the three sections or heads of the machine from the sprocket wheel 6 by a chain 7. The chain 7 passes from the sprocket wheel 6 on the stud 3 around the sprocket wheels 8 and 9 on the studs 4 and 5. To each of the 80 sprocket wheels 6, 8 and 9 on the studs 3, 4 and 5 a second sprocket wheel 11, 12 and 13 is affixed by which the parts of each head or section are driven by the chains 14, 15 and 16 (see Fig. 4.)

Instead of the sprocket wheels 6, 8 and 9 and chain 7 thereon the several parts may be 90 geared together by shafts and gear wheels beneath the gear plate M.

The gear plate M is made of such a shape 95 and size as to carry the driving gear and shafts necessary to operate three heads or sections with three inner carriages G and inner comb circles g. If desired the plate may be made of a size and shape adapted for four 100 or more heads or sections.

The carriages A and G are driven from the sprocket wheel N on the upright spindle n². The outer carriage A is driven direct from the spindle n² by the pinion n³ thereon gearing 105 with the rack a³ and the inner carriage G with the inner comb circle g is driven from the shaft n² through the gearing n' by the pinion n⁴ on the end of the upright spindle n which gears with the rack g' of the carriage G. 110

The central spindle K of the pillar H is driven by the sprocket wheel k and on the top of the spindle is a pulley h^2 from which the disks O are driven which press the fibers between the pins of the comb circles B and g.

The outer drawing off rollers D are driven by the sprocket wheel d' and spindle d^2 and the inner drawing off rollers F are driven by the sprocket wheel f and spindle f' .

- 10 By this construction of machine and arrangement of driving there is considerably less vibration in the operative parts of the machine and in consequence we are enabled to set the comb circles nearer to each other 15 and the drawing off rollers nearer to the comb circles thereby obtaining a greater quantity and better quality of production. Further a great desideratum is obtained in that several inner circle combs are driven in 20 sections one section by the chain 14, another section by the chain 15, and the third section by the chain 16, and where four combs were employed the fourth would be driven in a similar manner by a fourth chain. Should 25 one comb be damaged or become inoperative it is not necessary to stop the whole machine but by removing one of the chains one section of the machine can be stopped and the inner comb circle removed, while the others 30 continue to work equally efficiently.

What we claim as our invention and desire to protect by Letters Patent is:—

1. In a Noble combing machine the combination with a single outer comb carriage 35 an outer comb circle and a plurality of inner working sections of a single bracket with a plurality of arms upon which the several working sections are mounted, and means comprising chain gearing by which the several sections are separately and independently driven and means whereby a section or sections can be driven while a section or sections remain at rest substantially as described and shown.

45 2. In a Noble combing machine the combination with the outer carriage A outer comb B and a plurality of working sections each section comprising an inner carriage and inner comb circle, short pillar, constructed without top gearing, over which the circle can be easily removed drawing off rollers, center driving shaft, driving spindles attached to the said rotating parts and chain sprocket wheels on each driving spindle, of

a number of chain sprocket wheels 11, 12, 13 55 one for each section and a separate driving chain for each section, by which the several parts of each section are driven independently of any other section, driving sprocket wheels, 6, 8 9 connected to the wheels 11, 12, 60 13 and a main driving chain thereon by which the several sections are driven substantially as described.

3. A Noble combing machine, comprising in its construction the combination with a 65 single outer comb circle, an armed bracket and a plurality of sets of working parts mounted on the said bracket each set comprising an inner carriage G inner comb circle g and drawing off rollers, of a chain sprocket 70 driving wheel,—6, 8, 9—for each set a main driving chain 7 engaging said wheels sprocket wheels —11, 12 and 13, driven thereby and chains 14, 15, 16 thereon by which each section of the machine is separately and independently driven, substantially as described. 75

4. In a Noble combing machine the combination with the outer carriage A the outer comb circle B and the supporting frame C the outer drawing off rollers D the feed holders E and the inner drawing off rollers F of a plurality of inner carriages G, inner comb circles g, each working with the outer comb B, a three armed bracket G' upon which the inner carriages are mounted, short pillars, H 85 without top gearing mounted on the said bracket, a base plate, M through which driving spindles pass, the spindle n with chain sprocket wheel N thereon the roller spindle D with chain sprocket wheel d' thereon the 90 spindle K with chain sprocket wheel k thereon, the roller spindle f' with chain sprocket wheel f thereon, the double driving chain sprocket wheels 13 and 9 the chain 16 by which the parts are separately and independently driven, and the chain 7 by which the several sections of the machine are driven substantially as described. 95

In witness whereof, we have hereunto signed our names in the presence of two subscribing witnesses.

JOSEPH COOPER.
JOHN FRANCIS WHITE.
LOUIS COOPER.
